Filed Oct. 9, 1961, Ser. No. 143,854

4 Claims. (Cl. 105—101)

This invention relates to a motive power unit for model railroads, and more particularly to a simple and inexpensive form of power transmission for model railroad motive power units.

Generally speaking, the subject invention comprises a distinct improvement over the well-known rubberband drive systems for model railroad locomotives principally in the forms of: a single extensible flexible belt drive made of a helically coiled metal or a web of resilient plastic and bighted about the drive shaft and about a plurality of wheeled axles of a truck assembly; fair lead (funnel) guide means surrounding the drive belt between the drive shaft and the truck assembly and serving essentially as a ball and socket pivot joint between the locomotive unit and its truck assembly; and preferably a jack shaft and fly wheel combination for actuating the novel drive belt system by means of a high-speed, low-torque motor drive. Additionally, the drive shaft is provided with a pulley disc having V-notched recesses therein and the driven wheeled axles are correspondingly provided with V-notched recesses such that vastly improved drive characteristics and simulation of actual railroad operation are achieved. By incorporating the aforementioned principal features into the drive system of a scale model locomotive, it is feasible to use an inexpensive high-speed, low-torque prime mover and still obtain the operating characteristics desired in scale-model locomotive units.

In the prior rubberband drive systems, as exemplified by the teachings of United States Patent No. 2,903,974, issued to Robert M. Smith on September 15, 1959, a flexible drive belt comprising a rubberband is bighted under tension about a constant diameter drive shaft and about a reduced diameter portion of a singular wheeled axle. A low-speed, high-torque motor is required to rotate the shaft, which in turn rotates the rubberband drive belt. The essential operating feature of this prior art drive system resides in a slippage of the rotating shaft relative to the heat-sensitive rubberband drive belt until the inherent adhesive power of the rubber is developed by frictional heat, at which time the belt begins to turn under the influence of the rotating drive shaft. This initial start-up results in an undesirable and unrealistic jerking of the locomotive unit.

The slippage characteristics of the rubberband-type drive and the required utilization of a low-speed, high-torque motor to effect the desired drive have resulted in a locomotive operation which lacks the simulated realism of actual railroad structures which hobby enthusiasts strive for. Moreover, the tension under which the rubberband belt must be placed results in undue loads upon the motive source and in excessive friction and heat development at the bight points which tends to rapidly wear out the rubberband and thus to cause frequent breakdowns and necessities for repair.

Also, the rubberband belt tends to set during storage and shelf life and thus to exhibit irregular operating characteristics and likewise tends to hunt back and forth over the wheel axle and especially over the constant diameter drive shaft to further complicate the desired simulated characteristics of an actual railroad operation. Embodiments of the rubberband drive utilize one drive belt per wheel axle in order to achieve the desired slippage of the rotating band without which the rubberband drive system is incapable of functioning. When more than one

2

axle is present in the locomotive, as is invariably the case in scale model railroad equipment, the various rubberbands which are required must be very carefully matched and selected for co-active operation, since otherwise one rubberband will exhibit a tendency to impede the drive of another and thus to give poor pickup and running characteristics, especially on curves, switches, graded inclines, or other irregularities in the guiding tracks of the model railroad system.

It is a primary object of this invention to obviate the aforementioned difficulties exhibited by the prior art rubberband drive systems and to present an improved drive system for scale model locomotives which is characterized by ease of assembly and disassembly; by more realistic simulated characteristics of actual railroad operation without the need for expensive transformers to simulate gradual stop and start and incline ascending railroad characteristics; by inexpensive motive power means; and by increased driving ability per drive belt by virtue of the ability to utilize high-speed, low-torque motor structures with appropriate speed reductions so that one drive belt can drive two or more wheeled axles.

These and other objects, advantages, and features of this invention will hereinafter appear, and for purposes of illustration, but not of limitation, an embodiment of the invention is shown in the accompanying drawing, in which:

FIG. 1 is a side elevational view of a scale model locomotive constructed in accordance with the teachings of this invention and schematically showing the drive system in phantom lines;

FIG. 2 is a top plan view of the locomotive of FIG. 1 with the decorative carriage housing removed;

FIG. 3 is a bottom plan view of the locomotive of FIG. 1; and

FIG. 4 is a side sectional view taken along the line 4—4 of FIG. 2, showing the details of construction for the drive system.

In FIG. 1, the reference numeral 1 generally indicates the novel scale model locomotive. The locomotive scale model unit 1 comprises a decorative carriage housing 2 which is a scaled-down version of an actual railroad locomotive, a main frame 4 supporting the housing 2, and truck assemblies 6 and 8 which maintain the main frame 4 and its attached components in spatial relationship above the tracks 10 of the scale model railroad. The drive system for the locomotive unit 1 comprises an electric motor 12 positioned on the main frame 4 and gear drive means 14 actuated by the electric motor 12 to rotate a drive shaft 16 which is rotatably journaled within the main frame 4 and which in turn drives the truck assembly 8, in a manner to be subsequently described.

In more specific detail, the electric motor 12, which preferably comprises a high-speed low-torque electric motor, actuates a motor shaft 20 to which is rigidly affixed a drive gear 22. Jack gear 23, rigidly secured to drive shaft 16, meshes with the drive gear 22 in order to rotate the drive shaft 16 at a reduced speed relative to the rotation of the motor shaft 20. The drive shaft 16 is rotatably journaled within the main frame 4 as by positioning the ends of the shaft 16 in the bearing grooves 28, 32 of the bearing supports 26, 30 respectively. Preferably, the drive shaft 16 is journaled for free floating rotation relative to the main frame 4 whereby axial displacement of the drive shaft 16 relative to the frame 4 may be effected.

A dead weight housing 29 is located on the main frame 4 and is positioned such that the drive shaft 16 may rotate or axially displace within the grooves 25 and 25a oppositely disposed on the top of the housing 29. The dead weight housing 29 has a hollow interior 27 which surrounds both the bearing support 30 and an aperture 60

located in the base of the main frame 4. A dead weight cartridge 18 may also be secured to the main frame 4 in order to provide the desired overall weight distribution and characteristics which will best simulate actual railroad operation when the locomotive unit 1 is moved.

The drive shaft 16 is preferably provided with a pulley disc 34 rigidly secured thereto. The disc 34 has a V-notch 35 therein to provide a split sheave drive for the drive belt 36, in a manner to be subsequently described. The disc 34 is located on the drive shaft 16 in alignment with the aperture 60 of the main frame 4 so that the drive belt 36 which depends from the pulley disc 34 may encompass and drive the truck assembly 8, which is also positioned for alignment with the aperture 60 of the frame 4.

The truck assembly 8 has a generally H-shaped cross section and comprises side plates 40 spaced and joined by the cross bolster plate 42. A support frame 56 extends from the cross bolster plate 42 and has attached thereto a fair lead funnel 58 comprising an inverted bell-shaped funnel having a bottom diameter 68 and a narrower top diameter 66.

The aperture 60 of the main frame 4 is surrounded by a rectangular housing 62 which contains a circular opening 64 dimensioned to receive the top diameter portion 66 of the fair lead funnel 58. It is apparent that the truck assembly 8 with its attached fair lead funnel 58 may be positioned adjacent the main frame 4 by locating the fair lead funnel 58 within the aligned openings provided by the aperture 60 and the opening 64 such that the truck assembly 8 may be displaced both vertically and angularly relative to the main frame 4.

Metallic leaf springs 41 are positioned adjacent the side plates 40 of the truck assembly 8 by placing the springs 41 within the slots 43 located near the respective ends of the cross bolster plate 42 adjacent to the junction points where the bolster plate 42 and the side plates 40 are joined. The slots 43 may be dimensioned to securely seat the springs 41 therein without any additional attachments, or the springs 41 can be joined to the bolster 42 by conventional mechanical fasteners. The springs 41 are provided with detents 44 suitable for receiving the tapered ends 46 of the axles 47 which extend at either end of the truck assembly 8 between the parallelly aligned leaf springs 41. In the preferred embodiment of the invention, the springs 41 are constructed from a beryllium-copper alloy to afford the desired resiliency and to provide a current carrying capacity, for purposes to be subsequently described.

The axles 47 have wheels 50 rigidly secured thereon for rotation with the axle 47. The wheels 50 are provided with flanges 52 for engagement with the tracks 10 in a well-known manner. Between the wheels 50, an enlarged diameter portion 48 for the axle 47 is provided. The composite structure of the enlarged diameter portion 48, the wheels 50, and the concentrically disposed axle 47 with its tapered points 46 is hereinafter referred to as the wheeled axle 45. This composite wheeled axle 45 may be secured between the side plates 40 of the truck assembly 8 by suitable deflection of the leaf springs 41 such that the tapered points 46 of the axle 47 may be received within the detents 44 of the leaf springs 41. It is thus apparent that the wheeled axle 45 may be easily inserted and removed by a simple snap-in or snap-out movement relative to the truck assembly 8. The wheeled axle 45 is adapted for rotation relative to the truck assembly 8 by the bearing journaling of the taper points 46 within the detents 44.

The enlarged diameter portion 48 of the wheeled axle 45 is provided with a V-notch 54 at the central portion thereof. The drive belt 36 is rigidly seated within the V-notch 54 of at least two wheeled axles 45 each rotatably suspended within a truck assembly 8. The drive belt 36 is thus bighted about at least two wheeled axles

5 at its one end and bighted about the pulley disc 34 of the drive shaft 16 at its other end. In order to accommodate the different directions of rotation of the pulley disc 34 and the wheeled axle 45, the drive belt 36 is quarter-turned between its respective bight contacts. As best seen in FIG. 4, the portion of the drive belt 36 which extends between the bight portions surrounding the pulley disc 34 and the wheeled axles 45 feeds through the fair lead funnel 58, thereby securing the truck assembly 8 with its fair lead funnel 58 within the main frame 4 in a pivotable joinder.

In the preferred embodiment of this invention, a fly wheel 15 is attached to the motor 12 via a fly wheel shaft 13 to aid in the operation of the locomotive unit 1, in a manner to be subsequently described.

The operation of the assembled scale model locomotive can be described with reference to the truck assembly 8. The wheels 50 riding on the tracks 10 conduct current therefrom through the axle points 46 and into the conductive leaf springs 41. Wires (not shown) are suitably attached to springs 41 and lead to the motor 12, which is thereby energized. The energization of the motor 12 rotates the shaft 20 and its attached drive gear 22 in a direction determined by the polarity of the motor and the current fed thereto. The gear 22 in turn rotates the jack gear 23 which turns the drive shaft 16 rigidly attached thereto. As the drive shaft 16 rotates, the pulley disc 34 rigidly secured thereon likewise rotates, and the drive belt 36 bighted around the pulley disc 34 is caused to rotate, thereby rotating the wheels 50 in a given direction.

This drive sequence is accomplished without any slippage characteristics of the drive belt 36 relative to either the drive shaft 16 or the wheeled axles 45. The drive belt 36 is quarter-turned so that the wheels 50 will rotate in planes perpendicular to the plane of rotation of the pulley disc 34 when the respective V-notch 35 on the pulley disc 34 and the V-notches 54 on the wheeled axles 45 engage the drive belt 36 firmly grooved therein. These V-notches are preferably of a trough-shape cross-sectional configuration, the bottom portion of which is less in width than the diameter of the drive belt 36 so that the drive belt 36 will not slip relative to the V-notched grooves but is rather securely positioned therein by a biting action of the drive belt 36 into the side and preferably also the bottom walls of the V-notches. A disposition of the side walls at an angle of from 10 to 15 degrees from the vertical has been found most desirable when operating with a metallic helical coil as the drive belt 36.

50 Apparently, a very slight tension in the helical coil provides a series of bite teeth comprising each of the adjacent curved portions of the helix which, upon slight movement of the belt 36 relative to the V-notches, firmly grasp the surfaces thereof and rotate the member containing the 55 V-notch without any significant relative slippage.

The drive sequence is thus smooth and continuous within the truck assembly 8 and no significant slippage occurs between the belt 36 and either the pulley disc 34 or the wheeled axles 45. The fact that the belt 36 is bighted around more than one axle 48 further serves to minimize any slippage of the belt 36 within the truck assembly 8. Whatever slippage is involved in the locomotion of the scale model unit 1 is transferred from within the drive system (as in the prior art rubberband drive) to a slippage of the wheels 50 relative to the tracks 10, which characteristic simulates to a marked extent the driving characteristics of an actual full scale railroad locomotive.

70 The fair lead funnel 58 serves the dual functions of guiding the belt 36 as it rotates between the drive shaft 16 and the wheeled axles 45 while simultaneously serving as a ball and socket type joinder for the truck assembly 8 to the main frame 4. This structure allows a wide latitude of freedom of mobility for the truck assembly 8 relative to the main frame 4 in that angular rotation as well as 75 vertical displacement of the one component relative to the

other may be readily effected without disturbing the drive operation. In this fashion a free floating ride is observed which further aids in the marked simulation of the actual operating characteristics of a railroad operation and which likewise serves to minimize the possibilities of derailment. However, even if derailment should occur, the tracks are unlikely to be shorted out by virtue of the minimum of metal parts which have to be utilized in the truck assembly 8. Thus, only the wheels 59, the axle 47, and the springs 41 need be of metal, the remainder of the truck assembly 8 being constructed of plastic or other suitable non-conductive material.

It should also be noted that the free floating axially displaceable disposition of the drive shaft 16 relative to the main frame 4 also facilitates the desired freedom of mobility for the truck assembly 8 relative to the main frame 4. It has been found that the combination of this free floating disposition of the shaft 16, which of course provides for a variable disposition of the bighted end of the belt 36 about the pulley disc 34 relative to the main frame 4, coupled with the free floating connection of the truck assembly 8 to the main frame 4, provide an overall operation which closely approximates and simulates the drive characteristics of an actual railroad operation and which enable the locomotive unit 1 to be operated with a minimum of wear and tear and necessity for repairs. Thus the horizontal bounce and vertical sway of the assembled scale model unit 1 approximate the corresponding characteristics of an actual railroad locomotive, especially when the unit 1 passes over inclines, curves, switches, or other irregularities in the track system.

The motor 12, as described, is a high-speed, low-torque motor which is of a well known inexpensive type. The free floating jack drive effects a speed reduction of the shaft 16 via the meshed reduction gears 22, 24. Moreover, a dual speed reduction is involved in that the drive belt 36 itself effects a further speed reduction for the wheeled axles 45 by virtue of its engagement with the enlarged diameter portions 48 thereof such that the overall operation yields excellent start and stop characteristics. The free floating speed reduction for the high-speed, low-torque motor 12 allows a motor operation in its most efficient range and current consumption can be cut almost in half, as compared to the conventional motors utilized with rubberband type drives. Practically no load is impressed on the motor bearings, and a smoother and more reliable drive is exhibited. Also, the incorporation of the fly wheel 15 provides inertia to carry the locomotive unit 1 over irregularities in the track structure, such as curves, inclines or switches.

It is preferred that the drive belt 36 be bighted around more than one of the wheeled axles 45 in order to minimize slippage and frictional dissipation of energy, as previously described, and further in order to drive more wheels per belt, and, since hunting of the belts along the drive shaft is eliminated by virtue of the V-notch construction, it is possible to construct a scale model locomotive having a maximum of driven wheels for a given size. This feature is especially desirable where an incline climbing locomotive is desired.

Thus, more than one truck assembly 8 may be provided on a main frame 4, as desired, by suitable dimensioning of the locomotive unit 1. The drawing shows an idler truck 6 which is merely journaled for angular rotation relative to the main frame 4 as by the conventional screw attachment 70, but of course this idler truck assembly 6 could be readily adapted for replacement by another motive truck assembly 8 which functions in the manner previously described.

While the construction has been described with reference to a helical metallic coil as the drive belt 36, it should be understood that other types of belts may be utilized. For example, it has been found that endless bands of certain resilient plastics, such as polyformaldehyde, polytetrafluorethylene, nylon, and the like are

sufficiently rigid to bite into the V-notches of the split sheave pulley system and thus to exhibit the desired non-slip characteristics even when externally lubricated in addition to the inherent slippery characteristics of the specified materials. Correspondingly, it has been found that the pulley disc 34, the axles 48, or the fair lead funnel 58 may be constructed of similar materials. It is especially desirable to intercombine the materials as by constructing the belt 36 of metal and the axles 45, pulley disc 34, and fair lead funnel 58 of the described resilient plastics or vice versa in order to achieve the most positive non-slipping drive system.

Also, while a unitary H-shaped frame has been described for the truck assembly, it should be understood that the fair lead funnel guide and joinder structure could be located atop a multi-directional resiliently deformable truck assembly of the type described in the co-pending patent applications entitled Improved Truck Assembly for Model Railroads, Ser. No. 143,904, filed October 9, 1961.

It should be apparent that a novel and improved scale model locomotive has been described which obviates the deficiencies of the prior art rubberband type drives and which is characterized by the desired simulation of actual railroad operation at a minimum of expense and at a corresponding minimum of needed repairs. It should be understood that various changes and modifications may be made in the details of construction, arrangements, operations, and materials for the various elements without departing from the spirit and the scope of the invention, especially as defined in the appended claims.

What is claimed is:

1. In a vehicle for scale model railroads, the combination with an elongated frame having a longitudinal axis in the direction of motion of said vehicle, a truck assembly supporting said frame in spatial relation above track of said scale model railroad and comprising a plurality of wheeled axles, said frame having an opening extending therethrough and over said truck assembly; of an electrically energized motive power unit comprising a high-speed low-torque electric motor supported on said frame, a drive shaft rotatably journaled on said frame, mechanical coupling means interconnecting an output shaft of said motor to said drive shaft for communicating motive power thereto, linking means connecting said drive shaft to one of said wheeled axles for transmitting power from said drive shaft to said wheeled axles, said linking means comprising an endless drive belt bighted about said drive shaft and about said one of said wheeled axles, and fair lead means comprising a bell-shaped upstanding inverted funnel secured to and supported at its base on said truck assembly and extending upwardly through said opening in said frame and into a housing surrounding said opening and extending thereabout, said fair lead means providing low friction guide means for guiding the movement of said belt bighted about said drive shaft and one of said wheeled axles and constituting a mobile ball and socket type floating joinder of said truck assembly and the said frame to pivotally connect said truck assembly and said frame.

2. The motive power unit of claim 1 wherein said mechanical means connecting said output shaft to said motor comprises coupled speed reduction gearing, and wherein the endless belt comprises an extensible metallic helix, and wherein the drive shaft has a belt-receiving notch therein and the axles each have belt-receiving notches therein, the said notches each having a trough-shaped cross-sectional configuration, the bottom portion of which is less in width than the maximum diameter of

the endless belt, whereby the bighted belt is tensioned within the said trough-shaped notches for non-slip driving of the said wheeled axles.

3. The motive power unit of claim 1 wherein the endless belt comprises a band of substantially inextensible resilient plastic and wherein the drive shaft has a belt-receiving notch therein and the axles each have belt-receiving notches therein, the said notches each having a trough-shaped cross-sectional configuration, the bottom portion of which is less in width than the maximum diameter of the endless belt, whereby the bighted belt is tensioned within the said trough-shaped notches for non-slip driving of the said wheeled axles. 10

4. In a vehicle for scale model railroads, the combination with an elongated main frame having a longitudinal axis in the direction of motion of said vehicle, and a truck assembly comprising a plurality of wheeled axles, and means supporting said frame in spatial disposition above tracks of said scale model railroads, of a drive system for propelling said vehicle along said tracks, 15 said drive system comprising a high-speed low-torque electric motor supported on said frame, a drive shaft extending above and lengthwise of said frame and rotatably journaled thereon, coupling means connecting said drive shaft to a driven shaft of said motor, 20 said coupling means comprising a speed reduction gear system connecting said driven shaft to said drive shaft, 25

substantially non-slipping drive means for transmitting power from said drive shaft to said wheeled axles, said drive means comprising an endless belt bighted about said drive shaft and about said wheeled axles, fair lead means comprising a bell-shaped inverted funnel, said funnel being secured to and supported at its base by said truck assembly whereby said funnel extends upwardly through a floor opening in said main frame and into a housing surrounding said floor opening and extending thereabove, said fair lead means providing guide means for said belt bighted about said drive shaft and said wheeled axles and constituting a ball and socket type joinder for said truck assembly and said frame to pivotally connect said truck assembly to said frame.
